UNITED STATES PATENT OFFICE.

HENRY L. HOFFMANN, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed May 5, 1924. Serial No. 711,041.

This invention relates to telephone exchange systems and more particularly to improvements in trunk circuits for establishing connections between manual exchanges.

The invention is adapted for use in systems in which calls received at one manual exchange are extended by means of so-called A operator's cord circuits and trunk lines terminating in plugs at a so-called B operator's position located in another exchange where this latter operator may complete the connection by inserting the plug of a seized trunk line into the jack of a wanted subscriber's line. Ordinarily in such systems, each B operator is assigned to attend to a number of incoming trunk lines and her telephone set is manually connected to any seized trunk line by the operation of a key.

20 The trunk line to be used in each instance is usually assigned by the B operator by means of a separate call wire circuit extending between the operators in the two exchanges. In certain types of trunk systems, however, 25 this call wire service is dispensed with by having the A operator seize any one of the trunks leading to the desired B operator's position where means is provided for identifying the seized trunk.

30 Systems of this type are usually called straight forward trunking systems and it is an object of this invention to provide a greatly simplified system of this type in which the A operator may seize any available trunk leading to the desired exchange from which the wanted subscriber may be reached and whereby the B operator in such an exchange is automatically connected to a trunk line the moment it is seized and disconnected therefrom the moment she extends the connection to the wanted subscriber's line.

Another object is the provision of an arrangement whereby the manner of operating the usual signaling apparatus required for the proper supervision of the call is greatly simplified.

These objects are obtained in accordance with one feature of the invention by the use 50 of a switch and relay arrangement operated the moment a trunk is seized to automatically connect the B operator's telephone set thereto.

Another feature is the provision of a 55 greatly simplified circuit for telephonically

completing the connection between a seized trunk and the B operator's telephone set.

Another feature is the provision of a relay arrangement whereby the B operator's telephone set is disconnected from a seized trunk 60 the moment it is extended beyond without further operation of the switch.

Another feature is the provision in connection with each trunk of a signal and operating means therefor whereby said signal is 65 operated in one manner to indicate to the B operator that this particular trunk has been seized and in a different manner that her telephone set has been connected thereto.

Another feature is the provision of means 70 in the trunk whereby one signal indication is given when the A operator disconnects her cord circuit from a seized and extended trunk line and another signal indication if she again connects with this trunk line before the B operator has disconnected it from the previously called subscriber.

Another feature is the provision of means 75 whereby the ringing equipment used in trunks of this type is prevented from operating to ringer the previously called subscriber if the A operator attempts to establish a new connection over this engaged trunk.

Referring now to the drawing in which one embodiment of the invention is illustrated, there is shown on the left of the dotted vertical line a calling subscriber 10, whose line terminates in a jack 11 at the manual switchboard, an A operator's cord circuit A 80 and a jack 16 of a trunk T outgoing to another exchange. On the right of this vertical line is shown the incoming end of the trunk T terminating in a plug 17 and a wanted subscriber 20 whose line terminates 95 in a jack 18 at this exchange. Below the dotted line is shown a B operator's telephone set and associated equipment for automatically connecting her set to any one of a group of trunks such as T terminating at her 100 position.

In order to obtain a clear understanding of the invention illustrated, a description will be given of the functions involved in the setting up of a connection from subscriber 10 to subscriber 20. The calling subscriber 10 is connected by means of jack 11 and answering plug 12 to the A operator's cord circuit A and to her telephone set AOT 105 by means of the usual listening key as is 110

well-known in the art and the details of this connection need not therefore be further described. The A operator after having received from subscriber 10 the number of the 5 wanted subscriber's line inserts the calling plug 15 of cord circuit A into jack 16 of trunk T leading to the exchange through which the wanted subscriber 20 may be reached. This causes the operation of the 10 supervisory signal 14 in the cord circuit A as follows: battery, lamp 14, sleeve contacts of plug 15 and jack 16 to ground. Another circuit is also closed to operate relay 23 of T as follows: battery, lower right-hand winding 15 of repeating coil 17 of cord circuit A, winding of supervisory relay 13, ring contacts of plug 15 and jack 16, lower left-hand winding of repeating coil 22 of trunk T, right-hand and left-hand windings of relay 20 23 in series, upper left-hand winding of repeating coil 22, tip contacts of jack 16 and plug 15, upper right-hand winding of repeating coil 17 to ground.

Relay 23, in operating, initiates operations 25 resulting in the lighting of lamp 25 and the association of the B operator's telephone set BOT with the trunk T. The first circuit closes as follows: battery, lamp 25, armature and front contact of relay 23, lower armature 30 and back contact of relay 24, upper winding of relay 24, resistance 26, winding of relay 51 to ground. Lamp 25 is lighted in this circuit to indicate to the B operator that trunk T has been seized by the A operator.

35 The operation of relay 51 closes a circuit for the operating magnet 52 as follows: battery, winding of operating magnet 52, armature and back contact thereof, armature and front contact of relay 51, outer armature 40 and back contact of relay 53 to ground. The operating magnet 52 and switch 50 constitute the elements of the usual no normal position rotary step-by-step switches, well known in the art and the detail construction 45 of this switch and magnet need not, therefore, be further described except to say that the brushes 54 and 55 thereof are adapted to rotate one step each time magnet 52 is operated to contact with the terminals of 50 banks 56 and 57 respectively. It will be noted that the armature of magnet 52 will open the energizing circuit for the magnet each time it is attracted and the brushes 54 and 55 are therefore stepped forward in a 55 clockwise direction until they come in contact with the terminals connected to the conductors individual to the trunk T. At this time the energizing circuit for operating magnet 52 will be broken at the outer right-hand armature and back contact of relay 53 by the closing of the following circuit: 60 battery, lamp 25, armature and front contact of relay 23, lower armature and back contact of relay 24, conductor 27 and the associated terminal, brush 55, left-hand winding of relay 53 to ground. The brushes 54 and 55 will, therefore, remain on their respective terminals as shown. The operation of relay 53 closes a circuit for its right-hand winding and interrupter 60 as follows: battery, interrupter 60, inner right-hand armature and front contact of relay 53, right-hand winding of relay 53, left-hand winding of relay 53 to ground. When, therefore, interrupter 60 connects battery through this path, the path from battery at lamp 25 to ground at relay 53 will be shunted and the lamp extinguished. When the battery through interrupter 60 is removed the lamp 25 will again be lighted and this lamp 25 will therefore flash in accordance with the interruptions of battery at interrupter 60. This flashing of lamp 25 indicates to the B operator that her telephone set has been connected to trunk T.

The connection of the B operator's telephone set BOT to the trunk T takes place as follows: On the first operation of relay 53 the following circuit is closed: battery, winding of relay 62, armature and back contact of relay 63, outer right-hand armature and front contact of relay 53 to ground. The operation of relay 62 closes a circuit for the tone device 64 as follows: battery, lower right-hand winding of repeating coil 22, winding of relay 31, conductor 32, and the associated terminal of switch 50, brush 54, upper armature and front contact of relay 62, condenser 65, right-hand winding of repeating coil 66 to ground. The tone device 64 may be of any well-known type and the induced current through this repeating coil 66 to the last mentioned circuit is transmitted through the repeating coil 22 to the A operator's telephone set AOT connected to the tip and ring leads of the cord circuit A associated with trunk T and the operator is thereby notified that the B operator's telephone set is connected or is presently to be connected and that conversation may take place. This circuit for tone device 64 is only momentarily connected through to the A operator's position as the operation of relay 62 closes an energizing circuit for relay 67 as follows: battery, right-hand winding of relay 67, lower armature and front contact of relay 62, right-hand armature and back contact of relay 63, outer right hand armature and front contact of relay 53 to ground. The operation of relay 67 closes a locking circuit for itself as follows: battery, left-hand winding of relay 67, left-hand armature and front contact of relay 67, winding of relay 63, outer right-hand armature and front contact of relay 53 to ground. This locking circuit it will be noted passed through the winding of relay 63 which now operates opening the original energizing circuits for relays 62 and 67, and relay 62 is, therefore, released opening the circuit for the tone device 64. The release of relay 62

and operation of relay 67 now completes a circuit for the B operator's telephone set BOT as follows: battery, lower-right hand winding of repeating coil 22, winding of relay 31, conductor 32, brush 54, upper armature and back contact of relay 62, right-hand armature and front contact of relay 67, condenser 68, upper right-hand winding of repeating coil 69 to ground. The B operator's telephone set BOT is now inductively connected through the upper windings of repeating coil 69 to the A operator's telephone set AOT as shown and conversation between these two operators may now take place.

15 The B operator after having received the number of the wanted subscriber from the A operator inserts her plug 17 of trunk T into a jack 18 connected to the line of the wanted subscriber 20, that is to say after 20 she has performed the usual busy test well known in the art. This connection results in the operation of relay 24, extinguishing of lamp 25 and disconnection of the B operator's telephone set from the trunk circuit.

25 T. Relay 24 is operated over the following circuit: battery, lamp 25, lower winding of relay 24, ring contacts of plug 17 and jack 18 to ground. Relay 24 in attracting its lower armature opens the circuit at the back contact thereof for relay 53. This relay 53 releases immediately or as soon as the battery is removed by interrupter 60 and in releasing opens the holding circuit for relays 63 and 67. The release of relay 67 at its 30 right-hand armature and front contact opens the above mentioned circuit and thus causes the disconnection of the B operator's telephone set.

The operation of the lower armature of relay 24 closes a circuit for the application of 35 ringing current to the wanted subscriber 20 as follows: battery, winding of relay 28, lower armature and back contact of relay 30, armature and back contact of relay 29, lower 40 armature and front contact of relay 24, right hand armature and front contact of relay 23, lower winding of relay 24, sleeve contacts of plug 17 and jack 18 to ground. The resistance of the winding of relay 28 is of such 45 value as to shunt the path from battery through lamp 25 and thus cause it to be extinguished. The operation of relay 24 also causes at its upper armature and front contact the tip conductor of the trunk T to be 50 continued from the upper armature of relay 28 to the tip of plug 17. The operation of relay 28 connects ringing current to the 55 wanted subscriber as follows: ringing source 35, winding of ringing cut-off relay 29, lower 60 armature and front contact of relay 28, ring conductor of trunk T, ring contacts of plug 17 and jack 18 to the bell of the wanted subscriber's telephone set, back through the tip contacts of jack 18 and plug 17, upper armature and front contact of relay 24, tip con-

ductor of trunk T, upper armature and front contact of relay 28 to ground.

The subscriber at 20 in removing this receiver from the hook to answer this call causes ringing trip relay 29 to operate as is well known in the art and the operation of this relay opens at its armature and front contact, the shunt circuit for the lower winding of relay 30, and the circuit previously traced from battery at the winding of relay 28 to ground at the sleeve contact of jack 18 will now be closed through the lower winding of relay 30 causing this relay to operate in series with relay 28. However, the operation of relay 30 will immediately short circuit relay 28 by the closing of a path from battery at the lower armature and front contact of relay 30, through the winding of relay 30 to the ground at jack 18. Relay 28 in releasing removes the ringing source from the conductors to the called subscriber's line. A locking circuit is completed for relay 30 on the operation thereof as follows: battery, upper armature and front contact of relay 30, upper winding of relay 30, sleeve contacts of plug 17 and jack 18 to ground, thus making this relay 30 independent of the circuit through the armature and front contact of relay 23. The release of relay 28 now extends the talk- 95

operator now removes the plug 15 from jack 16 and lamp 14 is thereby extinguished and relay 23 released. Relay 23, in releasing, opens at its armature and front contact the 5 short circuit for lamp 25 through the lower armature and front contact of relay 24, winding of relay 30 to battery at its lower armature and front contact and the lamp 25 is thereby lighted to indicate to the B operator that the A operator has disconnected. 10 The B operator will thereby remove plug 17 from jack 18, causing relays 24 and 30 to be released and lamp 25 to be extinguished.

In case the A operator should again insert 15 her plug 15 in jack 16 before the B operator had removed her plug 17 from jack 18, this second connection will be noticed by the B operator through the extinguishing of lamp 25 as relay 23 will again be energized, the 20 short circuit for this lamp reestablished through the lower winding of relay 30 to battery. Subscriber 20 will however not be rung a second time as relay 30 is held operated at long as plug 17 remains in jack 18 25 due to the locking winding established from battery at the upper armature and front contact of this relay. The B operator on noticing that lamp 25 is again dark after having first been lighted, will know that 30 the A operator has disconnected the original calling subscriber from the trunk and is now connecting another subscriber thereto. She will then remove plug 17 from jack 18 and lamp 25 will then be lighted to affirmatively 35 indicate to her that the A operator has again seized the trunk and her telephone set will be connected to this trunk T a second time as hereinbefore described.

Should the A operator attempt to make 40 connection with another trunk such as the one that would be connected through resistance 40 to relay 51 while the B operator's telephone set is connected to trunk T, relay 51 will not operate as this relay will be 45 shunted by the ground through the left-hand winding or relay 53.

What is claimed is:

1. A telephone system comprising trunk 50 lines, means for seizing any one of said trunk lines at one end thereof, an operator's telephone set, a switch operated when one of said trunk lines is seized for finding said trunk line, means for connecting said telephone set to said seized trunk line operative 55 when said switch has found the seized trunk line, and means for disconnecting said telephone set from said trunk line without operating said switch when the seized trunk line is extended at the opposite end.

60 2. A telephone system comprising trunk lines, a cord circuit, an operator's telephone set, a switch operative when one of said trunk lines is connected to said cord for finding said trunk line, a circuit associated with 65 said telephone set, and means for connecting

said circuit to said switch operative when said switch has found the seized trunk line.

3. A telephone system comprising trunk lines, a first operator's position, means for seizing any one of said trunk lines at said 70 first operator's position, an operator's telephone set at a second operator's position, a selecting device common to said trunks associated with said telephone set, means responsive to the seizure of one of said trunk 75 lines at the said first operator's position for setting said selecting device into operation, and means operative when one of said trunk lines is seized at said first position for connecting said telephone set with said trunk 80 line through the medium of said selecting device.

4. A telephone system comprising trunk lines, means for seizing any one of said 85 trunk lines, an operator's telephone set, a circuit associated with said telephone set, a tone producing device, means operative when a trunk line is seized for momentarily connecting said device over a portion of 90 said circuit to said seized trunk line, and means for thereafter connecting said telephone set through said circuit to said seized trunk line.

5. In a telephone system comprising trunk lines, means for seizing any one of said 95 trunk lines at one end thereof, an operator's telephone set, a circuit associated with said telephone set, a tone producing device, means operative when a trunk line is seized for 100 momentarily connecting said device over a portion of said circuit to said seized trunk line, means for thereafter connecting said telephone set through said circuit to said seized trunk line, and means for opening said circuit to disconnect said telephone set from said seized trunk line operative when 105 said trunk line is extended at the opposite end.

6. A telephone system comprising trunk 110 lines, means for seizing any one of said trunk lines, a signal associated with each of said trunk lines, means for operating the associated signal when the trunk line is seized, an operator's telephone set, a switch operative when a trunk line is seized for finding 115 said trunk line, means for connecting the telephone set to said switch and trunk line when said switch has found the trunk line, and means for thereafter operating the associated signal in a different manner.

7. A telephone system comprising trunk 120 lines, means for seizing any one of said trunk lines at one end thereof, a signal associated with each of said trunk lines, means for operating the associated signal when a trunk line is seized, an operator's telephone set, means operative when a trunk line is seized for connecting said operator's telephone set thereto, means for operating said signal in 125 a different manner when the operator's tele- 130

- phone set is connected to the trunk, means for disconnecting said telephone set from the seized trunk when it is extended at the opposite end, means for disabling the signal 20
when a trunk is extended and means for again operating said signal if the seized trunk is released and for again disabling it if the trunk is again seized but still extended at the opposite end.
- 10 8. In a telephone system, the combination of trunk lines, means for seizing any one of said trunk lines at one end thereof, means responsive to the seizure of one of said trunk lines at one end thereof for connecting a telephone set thereto, means for 25 extending a seized trunk at the opposite end thereof to subscribers' stations, means responsive to the extension of a trunk line to a subscriber's station for disconnecting 30
- 15 said telephone set from said trunk line, means automatically operable substantially simultaneously with said last mentioned means for transmitting ringing current to said subscriber's station when a trunk line has been extended thereto, means for automatically discontinuing the ringing when the called subscriber answers, and means for preventing ringing signals from being again transmitted to the connected subscriber's station if the trunk line is released and again seized and for again permitting ringing signals to be transmitted if the trunk line is subsequently extended to another subscriber's station. 35

In witness whereof, I hereunto subscribe my name this 28th day of April A. D., 1924.

HENRY L. HOFFMANN.
